UNITED STATES PATENT OFFICE.

HELEN VON HARTZ, OF PAINESVILLE, OHIO.

DESIGN FOR A LAVALLIÈRE.

51,483.

Specification for Design.

Patented Nov. 13, 1917.

Application filed September 27, 1916. Serial No. 122,570. Term of patent 3½ years.

To all whom it may concern:

Be it known that I, HELEN VON HARTZ, a citizen of the United States, residing at Painesville, in the county of Lake and State of Ohio, have invented a new, original, and ornamental Design for Articles of Manufacture, of which the following is a specification, reference being had to the accompanying drawing, forming part hereof, wherein the figure is a face view of a lavallière exhibiting my new design, the same being selected as one of the many articles of manufacture wherein my new design may be incorporated.

I claim:—

The ornamental design for an article of manufacture, as shown.

HELEN VON HARTZ.

Witnesses:

HENRIETTA V. METZGER,
HARRY E. HAMMAR.
